UNITED STATES PATENT OFFICE.

JOHN GIBBONS, OF WEST TROY, NEW YORK, ASSIGNOR TO THE UNION
HARDWARE MANUFACTURING COMPANY, OF SAME PLACE.

HALTER-LOOP FASTENING.

SPECIFICATION forming part of Letters Patent No. 286,808, dated October 16, 1883.

Application filed May 2, 1883. (No model.)

To all whom it may concern:

Be it known that I, JOHN GIBBONS, of the village of West Troy, county of Albany, and State of New York, have invented a new and useful Improvement in Halter-Loop Fastenings, of which the following is a specification.

My invention relates to that class of devices which are used to fasten or attach the eye upon the rope, with which the clasp on the end 10 of the latter connects to form the lead-loop of the halter; and, my invention consists of certain improvements in the construction of this class of fasteners, which will be subsequently detailed herein, having for their object to simplify and better adapt such devices for the use 15 designed.

Accompanying this specification, and forming a part of it, are two plates of drawings, containing four figures, illustrating my invention, in all of which the same designation of parts by letter-reference is used.

Figure 1 shows a halter in perspective, with the clasp on the loop-end of the rope connected with the eye of my improved fastener to form 25 the lead-loop, with the loop-fastener in part detached from the rope to illustrate its interior construction. Fig. 2 exhibits in perspective the same parts of a halter that are shown in Fig. 1, with the fastener secured to the rope 30 and with the end clasp disconnected from the eye on the fastener. Fig. 3 illustrates in perspective one side of the eye and combined fastener; shown as detached from the rope. Fig. 4 exhibits another perspective of the eye and 35 combined fastener removed from its attachment, and with the side that is opposite to that shown in Fig. 3 as facing the view in this illustration.

The several parts of the device containing 40 my invention and those of the halter with which the former connects are designated by letter-reference and their function explained as follows:

The letter A indicates the head or nose strap connecting with the lead-loop B at a a, and E' the halter end of the rope, and R' the tether end of it.

The letter C designates the clasp on the halter end of the rope R', and E the eye on the

fastener, with which the clasp connects to produce the lead-loop B.

My invention relates entirely to the device on which and with which the eye E adjustably connects to the rope, and this is constructed of the half-cylinder D, which, at one end, e, 55 is drawn down and flattened in form to produce the ring or eye E, constructed with the opening O' in its semi-cylindrical surface at one end to receive the rope, and at its opposite end with the passage opening O², there being intermediately placed on its inner concave surface the projecting spur S. With the fastener and combined eye thus constructed the tether end of the rope is entered through the opening O', as shown at Fig. 1, and then passed 60 under the hook H through the passage-opening O², and that part of the rope between the openings forced down into the semi-cylinder part D and onto the spur S, where it is firmly held with the parts appearing as shown in Fig. 2. When 65 it is desired to increase or diminish the size of the lead-loop, the rope is passed from under the strap-hook H and pulled from off the spur S, and with the parts in the position shown at Fig. 1, when the fastener and combined ring may be 70 moved along on the rope through the opening O' to any desired length, and the device secured as before described.

Among the advantages arising from the use of my construction of ring and combined fastener is that when applied and secured to the rope the attachment to the latter is made on a line nearly parallel with it and without offset projection therefrom, and the convenience with which the fastener can be attached and 85 detached for adjustment.

I am well aware that two attached rings having a fixed connection at their edge and a side offset-eye for the clasp, with a spur between the rings, has been used for the same purpose; 90 and I am also aware that three fixed rings and a terminal eye for the clasp engagement have also been applied for the same uses, my improvement on these older devices consisting in the application of a grooved-out or semi-cylindrical 95 passage for the rope between its ingress and egress passage into and from the device, with a spur located on its concave interior, and the

substitution of a strap-hook for the egress of the rope instead of a ring under which hook to attach, or from under which to detach, the rope may be easily and promptly passed.

5 Having thus described my invention, what I claim, and desire to secure by Letters Patent, i3—

In a halter-loop fastening, the combination of the grooved-out or semi-cylinder D, which 10 at its clasp-attachment end is flattened out in form as indicated at e, the clasp-eye E on its flattened end, the strap-hook H on the end opposite to that on which the eye is placed,

the opening O', the passage O² for the rope, and the spur S, constructed on the inner concave face of said semi-cylinder, as and for the purposes herein described and set forth. 15

Signed at the city of Troy this 30th day of April, 1883, and in the presence of the two witnesses.

JOHN GIBBONS.
